UNITED STATES PATENT OFFICE.

WILLIAM H. WEHRENBURG, OF LA CROSSE, WISCONSIN.

PADDING.

1,352,231.

Specification of Letters Patent. Patented Sept. 7, 1920.

Application filed August 8, 1918. Serial No. 248,888.

To all whom it may concern:

Be it known that I, WILLIAM H. WEHRENBURG, a subject of the Emperor of Germany, residing at La Crosse, in the county of La Crosse and State of Wisconsin, have invented new and useful Improvements in Padding, of which the following is a specification.

The present invention comprehends generally improvements in that class of inventions known as weaving and more particularly relates to an improvement in padding.

It is the primary aim and object of the present invention to provide an article of the above mentioned character composed of a strip of batting which is peculiarly arranged to form superposed layers, the latter being held together forming a sheet which can be conveniently used in the making of comforts, et cetera.

It is an equally important object of this invention to provide improved means for reinforcing the strips when in a layer formed to relieve wear on the weaving or retaining cords, to maintain the sheet of padding in a sheet-like form and to prevent the same from sagging and becoming rough and uneven.

More particularly the present invention contemplates the provision of an article of the above mentioned character wherein improved weave or binding cords are associated with superposed strips forming the two layers of the batting for maintaining the side edges of the strips in close relation with each other and for forming bulb portions, the reinforcing strands being positioned for insuring the maintenance of the bulb portions in a substantial upright position so as to exert the strain imparted to the batting.

It is a further object of this invention to provide an article of the above mentioned character which is simple in construction, thoroughly reliable and efficient in its purpose and inexpensive in manufacture.

Other objects will be in part obvious and in part hereinafter set forth.

The invention accordingly consists in the features of construction, the combination of elements and the arrangement of parts which will be exemplified in the construction hereinafter described and the scope of the application of which will be indicated in the appended claims.

The invention is clearly illustrated in the accompanying drawings, in which:—

Figure 1 is a top plan view of a portion of a piece of padding.

Fig. 2 is a section taken on line 2—2 of Fig. 1.

Fig. 3 is a section taken on line 3—3 of Fig. 1.

Fig. 4 is a section taken on line 4—4 of Fig. 1.

Fig. 5 is a section taken on the line 5—5 of Fig. 1.

Fig. 6 is a perspective detail illustrating the assembly of the strips comprising the padding.

Fig. 7 is a diagrammatic plan view illustrating the assembly of the weave cords.

Similar characters of reference are employed in all of the above described views, to indicate corresponding parts.

Referring now, more particularly, to the accompanying drawings there is provided a pair of superposed layers or sheets indicated generally by the numerals 1 and 2 each of which comprise a plurality of transversely extending strips also arranged in superposed relation with transverse strips of the adjacent layer and these strips 3 are preferably formed from a single piece of strip-like cotton batting which is extended transversely to form one strip of the layer 1 and is folded upon itself as at 4 and extended transversely to provide the superposed strip of the layer 2 and is subsequently folded upon itself as at 6 in a manner similar to the fold at 4 to provide the superposed strip which is adjacent to the first strip provided and of the same layer; it is apparent that the several transverse strips may be provided by continuing this folding operation until the desired size of padding is obtained. Weave cords 7 are now provided and are arranged longitudinally of the base of the padding and in spaced parallel relation with each other and transversely of the strips 3 and over and beneath the adjacent pairs of strips of both of the layers as clearly indicated in Fig. 3, serving to hold the side edges of the adjacent strips 3 in close relation with each other. Other weave or retaining cords 8 are extended transversely of the piece of padding and between the adjacent strips 3 embraced by the weave cords 7 and these cords 8 cross the medial portions 9 of the cord 7 which embraces the adjacent pairs of the strip 3 so as to provide a plurality of squares 10. In this connection it is to be observed that

the cords 8 extend in spaced parallel relation with each other and are spaced in a similar manner to the cords 7.

To reinforce the weave and retaining cords 7 and 8 and to also prevent the padding from sagging and becoming uneven, suitable reinforcing means are provided in the form of relatively strong strands 11. These strands extend longitudinally 10 of a piece of padding and transversely of the strips being positioned between the strips of the layers 1 and 2 and also through the alined squares so as to maintain the squares in a bulb-like form and 15 thereby relieve wear on the weave and retaining cords. It is preferable that a plurality such as 3 or 4 reinforcing strands be arranged through the alined squares as indicated in the drawings.

20 In the manufacture of the article it may be preferable to arrange the reinforcing cords first on a frame, then wrap the piece of cotton batting in a manner mentioned to provide the layers 1 and 2 and finally arrange 25 the weave cords in position to provide a bulb-like square portion.

It is believed that a further description of the operation of the invention is entirely unnecessary. Likewise it is believed that the 30 advantages of the invention will be readily apparent.

It will be understood that the above description and accompanying drawings comprehend only the general and preferred embodiment of this invention and that various minor changes in detail of construction, proportion and arrangement of the parts may be made within the scope of the appended 35 claims and without sacrificing any of the advantages of this invention.

What is claimed is:—

1. An article of the character described consisting of a pair of superposed layers embodying transversely extending strips of batting, weave cords for retaining the strips 45

of each layer in close relation with each other and providing square portions, and longitudinally extending reinforcing strands engaged through the alined square portions and transversely of the strips.

2. An article of the character described composed of two layers each embodying transversely extending strips of cotton batting, and longitudinally and transversely extending cords interwoven about the strips 55 and interwoven with respect to each other for maintaining the strips of one layer in superposed relation with the strips of the adjacent layer.

3. An article of the character described 60 composed of two layers each embodying transversely extending strips of cotton batting, longitudinally and transversely extending cords interwoven about the strips and interwoven with respect to each other 65 for maintaining the strips of one layer in superposed relation with the strips of the adjacent layer and for maintaining the side edges of the strips of each layer in close relation with the side edges of the adjacent 70 strips, said weave cords forming square portions, and longitudinally extending reinforcing strands positioned through the alined square portions and transversely of the strips.

4. An article of the character described 75 consisting of a plurality of superposed layers formed from a single piece of strip-like batting material arranged to form a series of closely arranged superposed and transversely extending strips, weave cords interwoven 80 with the strips formed by the piece of batting material and interwoven with respect to each other to provide a plurality of square portions and reinforcing strands engaged transversely of the strips formed by a piece 85 of batting material in position between the layers and through the alined squares for holding the latter in bulb-like form.

In testimony whereof I affix my signature.
WILLIAM H. WEHRENBERG.
